UNITED STATES PATENT OFFICE.

RAY REDIFER AND FRANK E. CHADD, OF DANVILLE, INDIANA.

QUANTITATIVE OIL-DISPENSING BOTTLE.

Application filed May 7, 1921. Serial No. 467,574.

To all whom it may concern:

Be it known that we, RAY REDIFER and FRANK E. CHADD, citizens of the United States, residing at Danville, in the county 5 of Hendricks and State of Indiana, have invented a new and useful Quantitative Oil-Dispensing Bottle, of which the following is a specification, reference being had to the accompanying drawings, and to the letters 10 and figures of reference marked thereon.

This invention relates to a vessel that is designed to visibly hold a definite quantity of oil and in a convenient manner to be promptly delivered in retaining oils, especially to operators of automobiles, motor trucks and tractors, and to operators of various machines, the invention having reference more particularly to a vessel in which the oil may be conveniently carried and 20 from which the oil may be readily delivered into receptacles or reservoirs and the vessel left in possession of the retailer to be refilled.

An object of the invention is to provide a 25 carrying and dispensing vessel which shall be so constructed that it may be readily filled directly from a barrel or a shipping tank without waste of oil, so as to obviate the necessity of providing expensive tanks and 30 pumps commonly used in dispensing oils, the inconvenient use of cumbersome cans or the use of funnels with consequent loss of time of the retailer and the purchaser.

Another object is to provide a dispensing 35 vessel which shall be of strong and durable structure and yet permit the contents to be seen, in order that the retailer and also the customer may know that the quantity purchased is being delivered, and in clean condition as usually desired.

A further object is to provide an oil-dispenser which shall be so constructed that the oil container thereof may be composed of glass of strong form, and have a strongly 45 constructed dispenser spout firmly secured thereto and of sufficient length to be capable of safely supporting the container and contents, when the spout is inserted, and left in the filling hole of a reservoir while the oil is 50 being discharged into the receptacle where it may be required, an aim being to prevent the waste of oil during the different stages of the dispensing of the oil.

With the above-mentioned and other objects in view, the invention consists in an oil-dispensing bottle having improved struc-

tural features, more particularly relating to the features involved in the filling and the emptying of the bottle; and the invention consists also further in the parts and combinations and arrangements of parts as hereinafter particularly described and further defined in the accompanying claims.

Referring to the drawings,—Figure 1 is a fragmentary section of a reservoir or receiver of oil, such as the crank case of an explosion engine, with which the oil-dispensing bottle is arranged as when oil is being delivered to the reservoir; Fig. 2 is an elevation of the improved oil-dispensing bottle, on an enlarged scale; Fig. 3 is a bottom plan of the spout and vent tube therein of the improved oil-dispensing bottle, on a relatively larger scale; Fig. 4 is an elevation of the container on a small scale arranged in position to be filled directly from a shipping tank or barrel; and, Fig. 5 is a vertical central section of the upper portion of the oil-dispensing bottle, including the spout thereof, on a scale corresponding to Fig. 3.

Similar reference characters in the different figures of the drawings indicate corresponding elements or features of construction herein referred to in detail.

In practically carrying out the objects of the invention, a container is provided which is composed of glass and has a bottom portion 1 and a wall having a cylindrical body portion 2 permitting the containers to stand compactly together in a carrier. The wall has an inwardly curved shoulder portion 3 and a nearly straight neck portion 4 which has ample diameter that may be grasped in the hand when carrying or handling the container. The neck portion has an external bead or rib 5 which prevents the container from slipping through the hand when being carried. The container has also a mouth portion 6 extending upward beyond the bead 90 and it has coarse external screw threads 7 thereon, the mouth portion having a true top or end 8. The mouth of the container is very large in diameter to permit oil to flow in a stream into the mouth without requiring the use of a funnel. A gasket or joint ring 9 composed of suitable material is placed on the top 8 to prevent leakage. An improved spout is provided which comprises an annular base portion 10 that is 100 seated upon the gasket and has a flange 11 thereon to embrace the mouth portion 6, the

flange having screw threads 12 struck up thereon that engage the screw threads 7. The flange preferably has a flaring extremity 13 adapted to bear on the bead 5 to assist in forming a firm connection of the spout with the container. The base portion 10 has an annular neck 14 thereon and also an inwardly extending anchor plate 15 having an aperture 16 therein, the anchor plate 10 preferably being composed of a portion of the metal of the neck 14. The spout has a body portion 17 which is preferably tapered and has considerable length, approximately two-thirds of that of the container, the 15 larger portion thereof having a flange 18 or suitably curved flared portion that embraces the neck 14 and is suitably secured thereto and to the base portion 10. The outlet portion 19 of the spout has sufficiently large diameter to permit oil to flow out with considerable rapidity. A vent tube is provided which has a straight body portion 20 that extends through the aperture 16 and is suitably secured therein and it has an open inlet portion 21 arranged in the outlet end 19 of the spout, the tube extending along the inner side of the wall of the spout and being suitably secured thereto, and the tube extends into the container a suitable distance, preferably so that its outlet or inner end 22 is located in proximity to the bottom of the container. The large container neck and mouth and the large spout are ample to receive a vent tube of large diameter to 30 permit air to rapidly enter the container so that the oil may rapidly flow out.

It is designed that each container shall hold a definite quantity of oil, either by weight or measure, one size having one pint 40 capacity, another size having one quart capacity, and larger sizes as may be desired.

In practical use, the filled bottle is inverted with the spout inserted in an inlet 28 of a reservoir 24, the long spout permitting oil to be easily supplied to receivers when the latter may not be readily reached when delivering from the spout of a large can as commonly, and in some cases the bottle may stand at an inclination and be bodily supported by the spout, permitting the oil to quickly flow out. In case the receiver becomes sufficiently filled before the bottle is empty, the orifice of the neck and the vent tube become closed to the atmosphere by 55 the rising oil in the receptacle, so that the air cannot pass into the bottle and the oil is prevented from flowing out; and in such case the bottle may be removed and the remaining oil saved therein. In case there 60 be a strainer in the inlet opening of the receiver or reservoir, the oil may flow slowly through the strainer and accumulate in the inlet opening, which will result in the closing of the vent tube and temporarily stop 65 the flow of the oil from the bottle until ac-

cumulation passes through the strainer and permits the air to again enter the vent tube, when the discharge of the oil again automatically occurs, such action occurring repeatedly until the bottle is emptied or the reservoir becomes sufficiently filled. In every case the purchaser can readily ascertain the quantity of oil delivered to him. The dealer customarily retains the bottle and therefore the purchaser is not required 75 to pay for a container, even though inexpensive, for which he may have no future use, although in emergency the oil necessary to a long trip could be carried in the bottles and always ready for use. Customarily the dealer removes the spouts and quickly fills the containers under a faucet 80 connected to a shipping tank or barrel 25; and being enabled to see when a container is filled, he can promptly stop the 85 flow of the oil and not permit overflow and waste.

Having thus described the invention, what is claimed as new is—

1. A quantitative oil-dispensing bottle 90 comprising a container, a straight tapered spout having a base portion provided with an anchor device extending inward from the side thereof, the base portion of the spout being connected to the container, and a separate straight vent pipe arranged in the spout and extending through and secured to the anchor device, the pipe extending into the body portion of the container at an inclined angle relatively to the container. 95

2. A quantitative oil-dispensing bottle comprising a container with a large mouth, the top of the mouth wall being true, the outside of the wall of the mouth having 105 screw threads thereon, a packing ring seated upon the top of the mouth wall, a straight tapered open spout having a base portion seated upon the packing ring and a flange embracing the mouth wall, the flange being 110 provided with screw threads engaging the screw threads on the mouth wall, and a separate straight vent tube secured to the inner side of the spout and extending through said base portion and said ring into the 115 container, the vent tube having an inclined angle throughout relatively to the container.

3. An oil-dispensing bottle comprising a container consisting of a bottom, a cylindrical body wall portion from which extends an inwardly-curved wall portion, a neck wall portion extending from the inwardly-curved portion and having a large circumferential rib thereon to afford hand-hold, the neck portion being only slightly smaller in diameter than the body portion, and a mouth wall portion extending beyond said rib and having screw-threads on the outer side thereof adjacent to said rib, the 120 125 130

top of the mouth wall portion being flat; a straight tapered open spout having a separate base portion secured thereto and provided with a flange having screw-threads 5 engaging the screw-threads on said mouth portion, said flange extending approximately to said rib, a packing ring between said mouth top and said base portion, and a separate straight vent tube arranged on 10 the inner side of said spout and secured thereto, said tube being inclined to the longitudinal axis of the spout and extending through said base portion and said ring and freely through said mouth and neck 15 portions and nearly to said bottom and also to the smaller end of said spout.

4. In an oil-dispensing bottle, the combination with a container that has a neck, of an improved spout comprising an annular base portion to be seated upon said neck and having a neck thereon and also an inwardly extending anchor device, there be-

ing a flange on said base portion to embrace and engage the neck on the container, a straight tapered open spout that is approximately as long as two-thirds of the length of the container and having a flared portion embracing and secured to the neck on said base portion, the smaller end of the spout being squared, and a separate straight open 25 vent tube arranged on the inner side of said spout and secured thereto and to said anchor device, said tube being inclined to the longitudinal axis of the spout and of a length to extend nearly to the bottom of the container. 30

In testimony whereof, we affix our signatures in presence of two witnesses.
